UNITED STATES PATENT OFFICE.

CHARLES H. JOHNSON, OF SACRAMENTO, CALIFORNIA, ASSIGNOR OF ONE-HALF TO
ARTHUR E. MILLER, OF SACRAMENTO, CALIFORNIA.

HAMMER.

1,411,918.

Specification of Letters Patent. Patented Apr. 4, 1922.

Application filed September 4, 1919, Serial No. 321,553. Renewed March 30, 1921. Serial No. 457,026.

To all whom it may concern:

Be it known that I, CHARLES H. JOHNSON, a citizen of the United States, residing at Sacramento, in the county of Sacramento 5 and State of California, have invented certain new and useful Improvements in Hammers, of which the following is a specification.

My invention relates to certain new and 10 useful improvements in tools, such as hammers provided with a supplemental claw which serves as a nail extractor, and the invention consists, essentially, of a tool having a main claw with a substantially V-shaped groove formed in its side face, said groove being positioned at a point which approximates the center of the pulling surface of the main claw; in other words, the groove is made in the side of the tool about 15 midway between the axis of the usual socket and the outer end of the usual curved main claw, so as to equalize the pulling strain, whether the handle of the tool is forced towards or from the floor or surface from 20 which the nail is to be extracted, said groove, preferably, increasing in depth from the inner to the outer surface of the main claw and the deepest portion of the groove being at the smaller end, the walls of the groove 25 at this point forming substantially a square opening when viewed from the outer curved surface of the main claw.

In the accompanying drawing forming 30 part of this specification and in which similar reference characters indicate like parts in the several views;

Fig. 1 is a side elevation of a hammer embodying my invention.

Fig. 2 is an end view.

Fig. 3 is a cross section on the line 3—3 of Fig. 1.

In the present drawing I have illustrated 40 my improvement in connection with a conventional form of hammer wherein the head, 45 *a*, the socket, *b*, the handle *c*, and the claw, *d*, are of the usual type, the claw being curved from the eye or socket, *b*, to the outer end, this curved portion serving as a fulcrum when rocking the tool to extract a nail. In 50 the side of the hammer at a point which is approximately midway between the outer end of the main claw and the center of the eye or socket, *b*, is made a groove, *e*, the major axis of which is about coincident

with a line drawn radially from the center 55 from which the curve of the main claw is struck; in other words, the major axis of the groove stands at an angle of about 52 $\frac{1}{2}$ degrees to a line drawn longitudinally through the axis of the handle and socket, 60 as illustrated at *f*—*f*.

The groove is preferably V-shaped, the inner end being at and opening through, the inner curved surface of the main claw, *d*, the side walls of the groove converging and 65 leading through the outer curved surface of said claw. The groove also deepens from the inner to the outer surface of the main claw, which results in an inclined floor or bottom, *g*, and the formation of a substantially square opening, *h*, in the outer surface of the claw, *d*, the side walls of the groove and the said inclined bottom or floor being 70 preferably roughened or serrated to obtain a better gripping action on the nail to be 75 extracted.

By locating the groove at the point indicated and heretofore described the longitudinal axis or center thereof is located approximately in the center of the fulcrum or 80 curved pulling surface represented by the curved outer surface of the main claw, and when the groove is thus located, the pulling strain exerted is about the same whether the handle is forced downwardly towards 85 the floor or surface containing the nail to be extracted, or upwardly or away from said floor or surface. This facilitates the extraction of the nail and permits the tool to be successfully worked in situations where 90 other supplemental claws would be next to useless and which latter, ordinarily, can exert the pulling force only when the tool is operated in one direction.

The supplemental claw is not designed to 95 take the place of the main claw of the tool but is supplementary thereof and enables nails to be extracted from places—say close to vertical partitions, walls, etc., where the main claw could not be successfully applied 100 thereto. Further, by sloping the bottom, *e*, said groove at the inner surface of the claw substantially merges into the outer surface of the side of the tool, while the active portion of the supplemental claw is substantially 105 in the form of a rectangular opening, *h*, exposed through the outer curved surface of the main claw.

Having thus described my invention what I claim as new and desire to secure by Letters Patent is:—

1. A tool having a curved main claw said claw having a groove with converging walls formed in its side, the major axis of said groove being substantially radial of the center from which the curve of the main claw is struck, and the bottom of said groove declining from the inner to the outer surfaces of said main claw.

2. A tool having a curved main claw said claw having a groove with converging walls formed in its side, the major axis of said groove being substantially radial of the center from which the curve of the main claw is struck, the bottom of said groove declining from the inner to the outer surfaces of said main claw, and the walls of the groove being roughened.

3. As an article of manufacture, a hammer having a handle, a socket therefor and a curved main claw, said claw having a

V-shaped groove in its side substantially midway between the axis of the socket and the outer extremity of the claw, the major axis of said groove being substantially coincident with a line drawn radially from the center from which the curve of the claw is struck whereby the groove is disposed approximately in the center of the pulling area of the claw and the pulling force is exerted with substantially equal effect whether the handle is moved towards or from the work.

4. A tool having a segmental claw provided in its side substantially midway of its length with a substantially radially-extending groove, said groove decreasing in width and increasing in depth from the inner to the outer surfaces of the claw, and the outer end of said groove being substantially square in cross-section.

In testimony whereof I affix my signature.

CHARLES H. JOHNSON.
